(57) **CLAIM**

The ornamental design for a step, as shown and described.

DESCRIPTION

FIG. 1 is a front, top perspective view of a step, showing my new design;

FIG. 2 is a rear, bottom perspective view thereof;

FIG. 3 is a front elevational view thereof;

FIG. 4 is a rear elevational view thereof;

FIG. 5 is a left side view thereof, shown enlarged for ease of illustration;

FIG. 6 is a right side view thereof, shown enlarged for ease of illustration;

FIG. 7 is a top plan view thereof;

FIG. 8 is a bottom plan view thereof;

FIG. 9 is an enlarged detail view showing area 9 in FIG. 3;

FIG. 10 is an enlarged detail view showing area 10 in FIG. 4; and,

FIG. 11 is an enlarged detail view showing area 11 in FIG. 8.

The dashed broken lines illustrate portions of the step that form no part of the claimed design. The dash-dot-dash broken lines depict the boundaries and lead lines for the enlarged detail views and form no part of the claimed design.
